H. J. WARTHEN.
ELECTRIC SIGNAL FOR RAILROADS.
APPLICATION FILED JUNE 24, 1912.

1,090,360.

Patented Mar. 17, 1914.

UNITED STATES PATENT OFFICE.

HARRY J. WARTHEN, OF WASHINGTON, DISTRICT OF COLUMBIA.

ELECTRIC SIGNAL FOR RAILROADS.

1,090,360.

Specification of Letters Patent. Patented Mar. 17, 1914.

Application filed June 24, 1912 Serial No. 705,619.

To all whom it may concern:

Be it known that I, HARRY J. WARTHEN, a citizen of the United States, residing at Washington, in the District of Columbia, have invented certain Improvements in Electric Signals for Railroads, of which the following is a full and complete specification.

10 My invention is an improvement in electric signal apparatus for railroads, and relates more especially to those devices, as an electric-plow and ramp-rail, for making electric connection between a moving train and conductors alongside the track.

15 My invention is especially adapted for use in connection with railroads in which the train is provided with the customary air-brake mechanism in addition to the electric signal apparatus; whereby in case 20 the plow or any of the parts coöperating therewith should break or become disarranged the air-brakes on the train would be applied automatically, or a danger signal displayed; all as hereinafter fully described and specifically set forth in the appended claim.

In the accompanying drawings, which form a part of this specification: Figure 1 is a side view of an electric-plow, and connections, constructed in accordance with 30 my invention. Fig. 2 is a front elevation. Fig. 3 is a detail view of the electric-switch which is operated by the plow. Fig. 4 is a detail sectional view of the electric-plow. Fig. 5 is a diagram view illustrating a track 35 circuit which may be used in connection with my invention.

Like numerals of reference indicate like parts in all the figures of the drawings.

40 The present invention is part of an electric train-control system, for which I have filed an application for Letters-Patent of the United States on even date herewith.

In carrying out my invention I employ 45 in the first place a conventional form of electric-plow, consisting of an attaching-plate 5, secured to a side, as 6, of the car or locomotive of the train, a bracket-plate 7 bolted to said attaching-plate, and a shoe 8, pivoted to the lower end of the bracket-plate and projecting outwardly therefrom, said shoe being maintained in a normally raised position by means of a spring 9. In 55 the present instance the pivoted shoe 8 of the plow is hollowed out to form a closed cavity 10, and into this cavity projects a

pipe 11, connected to a pipe 12 extending from the train-line pipe 13 of the air-brake system, whereby, as will be understood, should either the shoe or pipe connections become broken or disconnected from any cause the air-pressure in the train-line pipe would be exhausted and cause an application of the air-brakes.

The pipe 11 being connected directly to the shoe of the plow moves therewith, and in order to permit of a free movement of said pipe a rubber-pipe connection 14 is interposed between the pipes 11 and 12, and in the present instance the pipe 11 serves to 65 operate the lever 15 of an electric-switch for connecting the wires 16 and 17 of an electric circuit, said pipe being connected to the switch-lever by a rod 18. The connections between the shoe of the plow and lever of the electric-switch are such that such lever engages the contact-point, as 19, to complete the circuit from battery 21 on the cab of the locomotive when the shoe is in its normally raised position, and is moved 70 beyond the switch-point when said shoe is depressed by engagement with the usual ramp-rail or conductor 20. Included in this circuit is a solenoid 22, which may operate any mechanical device or devices either to 75 display a signal or apply the air-brakes on the train, and in the present instance one of the wires, as 17, extending from a pole of the battery 21 is tapped to include said solenoid.

The ramp-rail 20 is one of the conductors of a partial track circuit adapted to connect with the cab-circuit and maintain the solenoid energized when the electric-switch is open; and this partial track circuit comprises the ramp-rail, connecting-wire 23, armature 24 of a track-relay 25, and a wire 26 connecting the contact-point 27 of the armature to one of the track-rails, as 28, the aforementioned armature being controlled 85 by any approved form of track-circuit. In the ordinary form of track-circuit the battery, as 29 (Fig. 5), is connected to the opposite rails of the track at one end of the block, and the relay 25 is connected to said 90 rails at the other end of said block, whereby when the battery is short-circuited, for instance by a train entering the block and shunting the current from the relay the latter is deenergized causing the armature to 95 drop. In the present instance, however, for the purpose hereinafter explained I have in-

cluded the supporting-posts, as 30, for the ramp-rails, in the track-circuit, and therefore one side of the relay is connected directly to the rail 28^b by wire 31, and the other side of the relay is connected by wire 32 to a plate 33 (Fig. 1) at the rear end of the supporting-post, and a second plate, as 34, at the forward end of said supporting-post is connected by wire 35 either directly to the other track-rail, 28^a, or in series with other supporting-posts, as shown in Fig. 5. This track-circuit may therefore be traced as follows: from one side of battery 29 to track-rail 28^a, wire 35, bearing-plate 34, base of supporting-post 30, bearing-plate 33, wire 32, relay 25, wire 31, track-rail 28^b to the other side of said battery. Now, as will be understood, the current may be shunted from the relay either through the wheels and axle of a train entering said block or a short circuit from any other cause; and, furthermore, the relay will be de-energized in case the ramp-rail is moved out of approximation with the plow by the displacement of any one of the supporting-posts 30, inasmuch as such displacement would break the circuit by moving the base of the post away from either one of the plates 33, 34. It will be understood, of course, that any displacement of the ramp-rail in a block would be detected or de-energize the solenoid on a train when it reached the adjoining block, inasmuch as the relay affected by the displaced ramp-rail is electrically connected with the ramp-rail in said adjoining-block, as hereinbefore described. In the present instance I also provide for de-energizing the solenoid 22 in case the electric-plow should become loose and displace the shoe with respect to the ramp-rails alongside the track, and for this purpose the supporting bracket 7 is provided with a projecting lug 7^a, which when the parts are in proper alinement or position is located midway between two conductors or contact-arms 36^a, 36^b of a plate 36 which is connected by a wire 37 to the wire, as 38, extending from said solenoid to the battery; whereby in case the lug 7^a engages either one of the contact-arms 36^a the current will be shunted from the solenoid, passing from one side of the battery by wire 16, switch-lever 15, connecting-rod 18, shoe 8, supporting-plate

7, lug 7^a, arm 36^a, plate 36, wire 37 and wire 38 to the other side of the battery.

55

In the operation of the devices for insuring a proper engagement of the electric-plow with the ramp-rails of a railroad provided with a track-circuit and a partial track-circuit, the latter including said ramp-rails, the current from the cab battery will pass through the partial track-circuit back to said cab-battery should all the parts be properly working and the partial track-circuit be unobstructed. On the other hand should the shoe of the plow break off or be disconnected from the pipe 11 the air-brakes on the train would be applied by the pressure being exhausted from the train-line pipe 13; or should the plow become displaced the solenoid 22 would be de-energized on account of the current from the cab-battery being shunted therefrom, and a similar operation would take place in case the ramp-rail in the block ahead of the train should become displaced, cutting out the track-relay in said block, and, of course, said track-relay would also be de-energized should a train be located in that block.

60

75

70

75

Having thus described my invention, what I claim as new, and desire to secure by Letters Patent, is:

80

In an electric signal and train control apparatus for railroads, the combination with a solenoid, an electric circuit controlling the same, a switch for opening and closing said circuit, a plow and a removable supporting member, a contact on said member, and connections between the plow and switch for operating the latter, of contact-plates above and below the aforesaid contact and normally out of contact, and electric connections between said plates and the conductors to the battery for shunting the current from the solenoid when the contact of said supporting member engages either one of the contact-plates, substantially as shown and for the purpose set forth.
